UNITED STATES PATENT OFFICE.

ALFRED P. SILVERTHORN, OF RIDLEY PARK, PENNSYLVANIA.

DEVICE FOR FILLING RECEPTACLES.

SPECIFICATION forming part of Letters Patent No. 633,913, dated September 26, 1899.

Application filed January 17, 1899. Serial No. 702,467. (No model.)

To all whom it may concern:

Be it known that I, ALFRED P. SILVERTHORN, a citizen of the United States, residing at Ridley Park, in the county of Delaware and State of Pennsylvania, have invented 5 certain new and useful Improvements in Devices for Filling Receptacles; and I do declare the following to be a full, clear, and exact description of the invention, such as will enable 10 others skilled in the art to which it appertains to make and use the same, reference being had to the accompanying drawings, and to the letters of reference marked thereon, which form a part of this specification.

15 This invention relates to new and useful improvements in devices for filling receptacles, and especially to an apparatus of this nature in which a double tube or two-way passage is provided in a spigot, one tube or passage-way being provided through which the liquid is designed to flow, while the other passage-way serves as a vent to allow air to replace the space from which liquid is drawn.

20 The present invention relates, further, to a filling device whereby an opaque receptacle may be filled or partially filled at different heights and the supply automatically cut off when the receptacle is filled to the neck of the filling-aperture or partially filled, as may 25 be desired, means being provided to prevent gurgling in the supply-reservoir and the passage of bubbles into the receptacle being filled.

25 To these ends and to such others as the invention may pertain the same consists, further, in the novel construction, combination, and adaptation of the parts, as will be hereinafter more fully described and then specifically defined in the appended claim.

30 My invention is clearly illustrated in the accompanying drawings, which, with the letters of reference marked thereon, form a part of this application, and in which drawings—

35 Figure 1 is a sectional view longitudinally through the filling-tube and the reservoir carrying same. Fig. 2 is a similar view showing a spigot having two passage-ways, said spigot being shown as applied to a stationary reservoir and one of the passage-ways being somewhat longer than the other and upwardly 40 bent. Fig. 3 is a sectional view of a cock 45 which may be employed in said spigot.

50 Reference now being had to the details of

the drawings by letter, A designates the reservoir, which may be small and portable, in which case the filling device may be held in 55 the neck of the reservoir, and when the spigot is used it is preferably to be applied to a stationary reservoir, as a barrel or can.

The filling-tube B is made with a longitudinal partition, making two passage-ways 60 through the tube or spigot, one of said passage-ways being somewhat smaller, the smaller duct or passage-way being indicated by letter D, which serves as a vent, and the larger one by letter E, through which latter 65 the liquid is designed to flow. The portion of the tubing outside of the reservoir carrying same is downwardly bent and adapted to be inserted in the filling-aperture of a receptacle which is to receive the liquid from the 70 reservoir. The inner end of the filling-tube on its under side is cut away, as at E', making the passage-way through which the liquid is designed to pass somewhat shorter than the vent passage-way, this shortening of the liquid 75 passage-way being for the purpose of preventing bubbles passing out with the liquid when the surface of the liquid in the receptacle being filled comes up adjacent to the end of the vent which is inserted in the receptacle. By 80 this provision the liquid will flow into the receptacle in a solid unbroken stream until the liquid ceases to flow.

When the spigot is used, preferably on larger reservoirs than in the construction 85 shown in Fig. 1, it is my purpose to have the inner end D' of the vent passage-way upwardly bent, so as to separate farther the openings at the inner ends of the spigot. At any suitable location in the spigot is the two-way valve H, whereby the flow of oil and air 90 through the passage-ways may be prevented.

In operation the end of the filling-tube is inserted in the receptacle to be filled or partially filled and the end of said tube held at 95 such a height in the receptacle at which it is desired to fill the latter and the liquid is allowed to flow into the receptacle until the surface of the liquid rises up to the openings in the outer end of the tube, when the vent 100 passage-way will be closed, not allowing any more air to enter the reservoir to replace the liquid, and the flow will cease. In order to prevent bubbles entering into the receptacle,

the inner end of the vent-tube being upwardly bent or extending farther in the reservoir than the under passage-way will separate the openings such a distance as to allow the liquid to flow in an unbroken stream until the receptacle is filled to the desired height.

By inserting the end of the tube or spigot into the filling-aperture of the receptacle, which may be done in case the receptacle is a fount for a lamp, while the lamp is burning the gases in the fount may be conducted away from the fount to the reservoir, thus avoiding possible explosions.

15 When my filling-tube is applied to a portable receptacle or reservoir, as a can, it may be securely fastened to a cap or a cork, as shown, and the shape of the tube or spigot and passage-ways therein may be varied with-

out departing from the spirit of the invention.

Having thus described my invention, what I claim to be new, and desire to secure by Letters Patent, is—

A device for filling receptacles, comprising 25 a spigot having a two-way passage through the same longitudinally, one of smaller capacity than the other, the longer of said passage-ways being upwardly bent, the two-way valve in the spigot, the outer end of which is 30 downwardly bent, as shown and described.

In testimony whereof I affix my signature in presence of two witnesses.

ALFRED P. SILVERTHORN.
